[57] ABSTRACT

A device is disclosed which relates to devices for vacuum-heating of materials. The device for electron-beam heating of materials, preferably for their melting and evaporation, comprises an electron-beam gun forming a ribbon electron beam; and an electromagnetic system for controlling said ribbon electron beam with a closed magnetic circuit having a rectangular shape and cores in which deflection coils are disposed, said device according to the invention being characterized in that the deflection coils are located on long opposing cores of said magnetic circuit, the short opposing cores of said magnetic circuit being mounted with additional coils for correcting and scanning of said beam, the deflection, correction and scanning coils being electrically associated with each other. The device may prove useful for melting and evaporation of metallic and non-metallic materials.

FIG. 3

FIG. 2

DEVICE FOR ELECTRON-BEAM HEATING OF MATERIALS MAINLY FOR THEIR MELTING AND EVAPORATION

BACKGROUND OF THE INVENTION

The present invention relates generally to devices for heating materials in a vacuum and more particularly, it relates to a means for electron-beam heating of materials, preferably for melting and evaporation thereof.

Some time ago, electron-beam guns with linear cathodes forming electron beams have found wide applications for vacuum-heating of materials. The direct heating of cathodes, the possibilities of enhancing the gun power by increasing the emitter area by increasing its length, and the use of accelerating voltages of up to 20 kV, with the simplicity of construction, distinguish the afore-said guns with the ribbon beams from axial electron guns having similar designation. However, an increase in the width of a sheet beam as well as constructional protection of a thermionic cathode from vapors and sputtered molten material lead to considerable difficulties in beam control (deflection, focusing and scanning). This resulted in a more sophisticated construction of the devices.

Thus in the known devices (cf. U.S. Pat. No. 3,409,729 Cl.13-31 and No. 3,114,656, Cl.313-75), to protect the electron-beam guns forming ribbon electron beams from vapors and sputtered molten material and to produce a differential vacuum, use is made of several electromagnetic beam control systems disposed in succession along the beam path.

Such devices, being relatively complicated in terms of their construction and featuring also large overall dimensions, require accurate matching of all the electromagnetic systems that are arranged in succession, but this fact materially impairs the reliability of operation of the above devices.

Also known are devices in which the deflection of the ribbon electron beam is effected by a single electromagnetic system comprising a rectangular closed magnetic circuit with short cores on which deflection coils are located generating a magnetic field which deflects the beam along the cathode, i.e., in the beam plane. However, constructional protection of the linear thermionic cathode from the vapors and sputtered molten material particles necessitates a substantial increase either in the length of a beam guide having an outlet with the deflection system arranged thereat or in a beam deflection angle which augments the overall dimensions of the device (especially when its power is increased by extending the cathode length) which adversely affects the quality of the beam formation.

A serious disadvantage of the devices lies also in the fact that the beam can be controlled only in one plane, which diminishes substantially the technological potentialities of the devices.

SUMMARY OF THE INVENTION

It is an object of the present invention to overcome the above mentioned disadvantages.

The present invention is in essence aimed at a provision of a device for electron-beam heating of materials mainly for their melting and evaporation, the device design being such as to ensure vacuum differentiation and protection of the electron-beam gun from vapors and sputtering. The device comprises a single-unit electromagnetic ribbon beam control system which enables

a slightly divergent sheet beam formed by the electron-beam gun to be deflected at an angle of up to 45° and to be concurrently focused and converted into a cylindrical beam, ensuring also correction of the beam path and its scanning in a plane perpendicular to the deflection plane.

This is attained by a device for electron-beam heating of materials comprising an electron-beam gun forming a ribbon electron beam and an electromagnetic system of control of said beam with a closed rectangular magnetic circuit having cores with deflection coils are arranged thereto, according to the invention, the latter being disposed on the long opposing cores of the closed magnetic circuit, the short-opposing cores of said magnetic circuit be mounted with additional correction and scanning coils, the deflection, correction and scanning coils being electrically associated with each other.

With optimum length ratios of the cores of the rectangular magnetic circuit the magnetic field of the deflection coils deflects the ribbon beam, ensuring also its concurrent focusing and conversion into the cylindrical beam.

Depending on the width of the ribbon beam, the optimum length ratio of the cores can be within the range of 1.2-5.

The deflection coils as well as those for correction and scanning are advisable to be coupled with each other in series.

Fine focusing of the deflected beam during its conversion into a cylindrical one or its focusing into a narrow long focal spot is performed by changing the ampere-turn ratio in these coils by connecting by-pass adjustable resistors to them so as to produce a nonuniform magnetic field of a requisite shape.

To connect the above by-pass resistors, the neutral point of the series-connected coils is advisable to be provided with a lead-out.

For scanning and deflection of the beam over the metal heating surface, the correction and scanning coils can be coupled to a D.C. current supply with an A.C. component having a pre-set amplitude and frequency.

The device accomplished in conformity with the present invention has proved successful in solving a number of major technological problems encountered in the melting and evaporation of both metallic and non-metallic materials; a relatively small increase in only one dimension of the device (by increasing only the length of a linear emitter) enables the rated power of the device to be enhanced up to 400-500 kW with the accelerating voltages not exceeding 20 kV.

BRIEF DESCRIPTION OF THE DRAWINGS

A fuller understanding of the nature of the present invention will be had from the following description of an exemplary embodiment of a device for electron-beam heating of materials mainly for their melting and evaporation and considered in conjunction with due reference to the accompanying drawings, wherein:

FIG. 1 is a sectional view of the device layout, according to the invention;

FIG. 2 depicts an electromagnetic system of the device, according to the invention, the shape of magnetic field and projections of three representative paths of the elements of a slightly divergent electron ribbon beam;

FIG. 3 is a wiring diagram of the coils of the electro-magnetic system of said device.

DETAILED DESCRIPTION OF THE PREFERRED EMBODIMENT

As can be seen from FIG. 1, the herein-described device comprises an electron-beam gun forming a slightly divergent ribbon electron beam and including a cathode assembly 1 with a linear thermionic cathode 2, a cathode focusing electrode 3 and an accelerating anode 4. With the aid of a beam guide 5 which is made in the form of a copper block fitted with passages 6 for cooling water and with rectangular openings for the passage of a ribbon beam 7, the accelerating anode 4 is designed to be coupled with an electromagnetic system of the device, which is a rectangular closed magnetic circuit 8.

Long cores of the magnetic circuit 8 carry two deflection coils 9 and 10 (FIGS. 1 and 2), its short cores being mounted two correction and scanning coils 11 and 12 (FIG. 2). The electromagnetic system is located in grooves of a copper water-cooled base 13 (FIG. 1).

As it is shown in the wiring diagram, each of the two deflection coils 9 and 10 (FIG. 3) and correction and scanning coils 11 and 12 disposed accordingly on the long and short cores of the rectangular magnetic circuit are connected in series, the end of one coil being coupled to the beginning of the other one, and a connection point of the deflection coils 9 and 10 is provided with a lead 14 to by-pass them with the aid of adjustable resistors R_1 and R_2 , the deflection coils 9 and 10 being coupled in series in such a manner that their magnetic fields are added together in parallel in the space between the cores and are directed across the incoming ribbon beam.

The length ratio between the short and long cores of the magnetic circuit 8 is chosen within the range of 1.2-5.

The slightly divergent ribbon beam 7 focused by the electron-beam gun and passing in the beam guide 5 is rectangular in cross-section (FIG. 2). The electrons passing in the transverse magnetic field of the deflection coils 9 and 10, indicated in FIG. 2 by solid lines, are deflected at right angles to the intensity vector of the magnetic field.

Due to a certain curvature of magnetic force lines depending to a considerable degree on geometric dimensions of the rectangular magnetic circuit with the foregoing coils disposed on it, the sheet beam, on being deflected, is subject to the condenser effect directed to the middle deflection plane having a projection as shown by a straight line AB.

FIG. 2 depicts the projections of the representative paths of the ribbon electron beam onto a focal plane which in this case is a horizontal plane being level with the point of collision between the beam and the object being heated.

At point "b" of a section of the beam 7, the electrons passing through the concave magnetic field are deflected at a certain angle to the middle plane AB. At points "a", "m" and "n" the electrons are deflected in the middle plane AB. The electron path projections of these representative points are shown by the straight lines "bb'", "mm'", "aa'" and "nn'". At point "c" the electrons which have first reached into a convex field will move along the path "cc'" and then, on being de-

flected into the concave field arc, are subjected within it to a prolonged effect and will follow the path shown by the line "cc'" directed also toward the plane AB.

Such interaction between the slightly divergent sheet electron beam with the magnetic field under consideration results in its deflection accompanied by a concurrent conversion of the sheet beam into a cylindrical one and by its focusing into a focal spot 15 on the object being heated.

Decrease of the focal spot 15 along the axis CD and its increase along the axis AB is achieved by attenuation of the field of the deflection coil 10 which is effected by by-passing its turns with the aid of the adjustable resistor R_1 (FIG. 2).

Decrease of the focal spot 15 along the axis AB and its increase along the axis CD is effected by attenuation of the field of the deflection coil 9 by by-passing it with the aid of the adjustable resistor R_2 .

Correction (displacement) and scanning of the beam 7 along the axis C'D' are effected by the transverse field of the coils 11 and 12 shown in FIG. 2 by dotted lines.

Concurrent correction and scanning is achieved by feeding the coils 11 and 12 with a direct current from a power supply E with an A.C. component of a pre-set amplitude and frequency.

What we claim is:

1. A device for electron-beam heating of materials, mainly for their melting and evaporation, said device comprising:

an electron-beam gun means forming a ribbon electron-beam and including an anode unit with an accelerating anode;

an electromagnetic system including a closed magnetic circuit having a rectangular shape, said electromagnetic system being disposed in said anode unit directly behind said accelerating anode for converting said ribbon electron-beam into a cylindrical one;

deflection coil means disposed on the long opposing cores of said rectangular magnetic circuit associated electrically with each other for deflecting said ribbon electron-beam in a plane perpendicular to the plane of the beam; and

correcting and scanning coil means disposed on the short opposing cores of said rectangular magnetic circuit and electrically associated with each other for deflecting said ribbon electron-beam over the surface of the material being heated.

2. A device as claimed in claim 1 wherein for focusing said beam in the form of a round spot on the surface of the material being heated, the length ratio between the cores of the magnetic circuit of said electromagnetic system is chosen within the range of 1.2-5.

3. A device for electron-beam heating of materials, mainly for their melting and evaporation, said device comprising:

an electron-beam gun means forming a ribbon electron-beam;

an electromagnetic system including a closed magnetic circuit having a rectangular shape for controlling said ribbon electron-beam;

deflection coil means disposed on the long opposing cores of said rectangular magnetic circuit associated electrically with each other for deflecting said ribbon electron-beam in a plane perpendicular to the plane of the beam, said deflection coil means

including coils which are series-connected for deflecting said beam being formed, said series-connected deflection coils having a lead-out from their neutral point to which by-pass adjustable resistors are coupled for providing a fine focusing of said beam being formed; and correcting and scanning coil means disposed on the short opposing cores of said rectangular magnetic circuit and electrically associated with each other

for deflecting said ribbon electron-beam over the surface of the material being heated.

4. A device as claimed in claim 3, wherein to provide the scanning and displacement of said formed ribbon beam over the metal surface being heated, said correction and scanning coils are connected to a D.C. current supply with an A.C. component of a pre-set amplitude and frequency.
